ADJUSTABLE HEAD GOLF CLUB

Rodger D. Brouwer, Bristol, Conn.

Application June 23, 1945, Serial No. 601,189

4 Claims. (Cl. 273—79)

1

This invention relates to golf clubs and particularly to a universally adjustable golf club.

During the usual game of golf, it is customary for each golfer to employ as many as seven or more different golf clubs, and these clubs are so cumbersome that it is usual for each golfer to employ a caddie to carry them around the golf course. The principal differences between these various clubs resides in the different angular relations of the club heads to their respective shafts and in the different lengths of shafts.

An object of my invention is to provide an improved universally adjustable golf club of simple rigid construction and which may be quickly and easily adjusted to various predetermined positions corresponding to those of the presently used golf clubs as well as to various other positions.

Another object is to provide a universally adjustable golf club which is particularly adapted for playing a golf ball from locations that have heretofore been considered inaccessible.

A further object is to provide a universally adjustable golf club adaptable to all departments of the game of golf.

A further object is to provide a universally adjustable golf club having a shaft which may be quickly and easily adjusted in accordance with the type of club to be used and in accordance with the reach of the golfer.

A still further object is to provide a universally adjustable golf club having the equivalent striking force of the usual driver, brassie and spoon, and having an improved striking force when adjusted to the various iron positions.

To these ends and also to improve generally upon devices of the character indicated, the invention consists in the various matters herein-after described and claimed. The accompanying drawings illustrate my preferred form of invention which has proved very reliable and highly satisfactory. However, it is to be understood that the instrumentalities of which my invention consists may be variously arranged and constituted, and that my invention is not to be limited to the precise arrangement and organization of instrumentalities shown and described.

Figure 1 shows a fragmentary face elevation of my golf club;

Figure 2 is a fragmentary heel or rear elevation of the golf club;

Figure 3 is a developed view showing the indicating mechanism used when adjusting the angle of loft of my golf club;

Figure 4 is an exploded perspective view show-

2

ing the mechanism for adjusting the angles of loft and lie;

Figure 5 is a fragmentary plan view;

Figure 6 is a fragmentary perspective rear view of the club head adjusting mechanism;

Figure 7 is a view, partly in section, of the shaft; and

Figure 8 shows the expansion plug for adjusting the shaft.

Generally considered, my club head 10, which has a flat striking face 12, is arranged for quick, easy, positive adjustment in a plurality of planes to various predetermined positions with respect to an adjustable shaft 14 so that my golf club is universally adjustable to serve efficiently in all departments of the game of golf, and is also adjustable to easily play a golf ball from beneath low hanging branches and from other positions heretofore considered normally inaccessible. A golfer, when using my universally adjustable club, becomes much more proficient at the game of golf in a short time since it is not necessary to become accustomed to clubs of different weight, sizes, and having different conditions of balance. The adjustable shaft 14 also facilitates shortening the club so that it may be conveniently carried in a suit case or with small hand luggage.

In the preferred embodiment of my invention, the club head 10 is generally oval shaped in plan view and may be composed of a suitable hard wood or of a fibrous material which may be molded. The mass of the head 10 is distributed behind the striking face 12 to aid the balance of the club and to produce over the entire face 12 a uniformly distributed zone of percussion which has a striking effect superior to that produced at the critically positioned "sweet spot" on the striking face of the usual golf irons and equivalent to that of the driver, brassie and spoon when my club is adjusted to these positions. A longitudinally curved sole plate 16 protects the lower forward edge of the head 10, and adds rigidity to the lower portion of the striking face 12. The head 10 has an underface 18 sloping upwardly and rearwardly from the sole plate with sufficient angular relation to the plane of the striking face 12 to allow for a loft angle adjustment for playing a ball out of a deep sand trap.

An anchor plate 20, provided with an outwardly projecting parti-cylindrical wall 22, having an arcuate slot 23 therethrough, is rigidly secured, as by screws 24, to one end of the head 10, and the axis A—B of this parti-cylindrical portion is preferably disposed perpendicularly to the plane of the striking face 12. A threaded stud

27 extends through the slot 23 and has a transversely curved head 28 arranged to matingly seat against the inside of the parti-cylindrical wall 22. A locking collar 30, slidably receiving the stud 27, has a concaved face 32 matingly engageable with the outside of the parti-cylindrical wall 22, and an annular set of radially extending similarly spaced generally V-shaped teeth 33 formed in the opposite end of this collar 30, are matingly engageable at desired angular positions with a corresponding set of teeth 34 formed in one end of an annular portion 35 on the lower end of a sleeve member 36 which constitutes the lower end of the adjustable shaft 14. A bore 37 through the annular portion 35, and disposed centrally of the annular row of teeth 34, slidably and rotatably receives the stud 27. Keyways, longitudinally cut through the collar 30 and opening onto the stud 27, slidably receive the opposite ends of a cross pin 38 radially projecting from the stud 27 to prevent relative rotation between this collar and stud during adjustment of the golf club. A hand lever 40, threaded on the outer end of the stud 27 and provided with an operating arm terminating in a convenient finger grip 41, may be tightened against a spring washer 42 to a position lying upwardly along the back of the sleeve member 36 for positively clamping the members 20, 30 and 35 against relative movement and thereby rigidly securing the club head 10 in any preadjusted angular relation to the shaft 14.

When the hand lever 40 is loosened, the club head 10 may be turned about the axis C—D of the stud 27 to regulate the angle of loft, this being the angle of the striking face 12 with respect to the general plane of the ground beneath the head 10 at the instant of ball impact. Also, when this hand lever 40 is loosened the head 10 may be adjusted with respect to the shaft in the plane of the shaft axis and the axis C—D since the parti-cylindrical wall 22 may be frictionally moved between the stud head 28 and the collar face 32 about the axis A—B to regulate the angle of lie as shown in Figure 1. These adjustments for the angles of loft and lie may be made independently or simultaneously as desired. I preferably loosen the hand lever 40 only sufficiently to partially release the tension of the spring 42 so that the teeth 33 and 34 may be snapped past each other to desired adjustment and the wall 22 will be sufficiently gripped between the head 28 and the collar 30 so that the club head 10 will remain at its preadjusted angles of loft and lie while the hand lever 40 is again tightened.

For clarity, I have illustrated indexing of my universally adjustable club to only seven different positions which include the types of clubs most frequently used, these club positions being designated as follows: W, a club for driving a spinning ball having a downward turning movement in a wind D, driver, P, putter, B, brassie, S, spoon, A, approach and M, mashie. However, many other club adjustments may also be obtained by adjustment of the angles of loft and lie. The locking collar 30 is bevelled to provide an index 44 (Figure 6) that may be brought into desired selective register with indices D, P or A on the wall 22 for adjusting the angle of lie of the club head 10. Locating the index 44 at D produces the correct angle of lie for the driver, brassie, spoon and wind ball club adjustments. The index 44 is positioned at P for a putter and at A for a mashie or approach club. To procure the desired adjustments for the angles of loft for these various clubs, these letters W, D, B, S, A

and M are successively stamped across the mating teeth 33 and 34 and in spaced relation about the coincident peripheries of the locking collar 30 and the annular portion 35. As shown in Figure 3, only one of these letters has its parts at each side of the mating teeth in registering alignment at the same time, and relative rotation of the members 30 and 35 to produce such registration results in the correct loft angle for the letter in registration. For example, with the letter S in register and the index 44 at D, the club is adjusted as a spoon. The loft angle for a driver and a putter is the same. Hence, with a loft adjustment at D and with the index 44 at P, the club head and shaft relation are correct for a putter. I preferably have the mating teeth 33 and 34 of sufficiently small size so that the loft angle adjustment will be through small increments to provide for club adjustments intermediate of those indicated. Also, the wall 22 may be adjusted between the head 28 and the collar 30 to provide an angle of lie sufficiently obtuse to drive a ball out from beneath a low branch, or if desired this angle of lie may be adjusted sufficiently in the opposite direction to play a ball from close to a golfer's feet.

The tubular shaft 14 is adjustable for length to compensate for the reach of different golfers and to provide a shortened shaft when the club 30 is used as a putter. An intermediate shaft portion 46 has a tapering lower end which may be hand wrung into tightly nested relation over the tapered upper end of the sleeve member 36 and locked in position by a tapered pin 47 detachably 35 and transversely extending through these nested members. A flexible wire secured to the tapered pin and to the shaft portion 46 prevents loss of the pin when withdrawn. A sleeve 48, slidably fitted for longitudinal adjustment over the upper 40 end of the intermediate shaft portion 46, is provided with a hand grip 50 of leather or other suitable material, and is closed at its upper end by a cap 52. An expandable plug 53, secured against rotation within the upper end of the 45 intermediate shaft portion 46, has an eccentric through bore 54, and a slot 55 extends from this bore to the plug periphery. A locking member 56, journaled in the bore 54 and secured in position by a cotter pin, has a radially extending 50 arm 57 that holds a spring 58 in frictional engagement with the interior wall of the sleeve 48. Turning of the sleeve 48 on the member 46 frictionally acts through the spring 58 to turn the locking member 56 within the bore 54 causing 55 an expansion of the split plug 53 which expands the shaft portion 46 into locked relation with the sleeve 48 to secure this sleeve in its longitudinally preadjusted position. A flexible wire 60, secured at its upper end to the cap 52, extends through a bore 61 in the locking member 56 and has at its lower end an abutment which will engage the locking member and prevent removal of the sleeve 48 from the shaft portion 46.

56 A clamp 64 provided at the split lower end of the sleeve 48 augments the locking device within the shaft portion 46 and prevents this sleeve from rocking in locked position. If desired, index marks, as P and D, may be provided on the intermediate shaft portion 46 for registration with the lower end of the sleeve 48 for convenience in adjusting the length of the shaft 14. When it is desired to compactly transport my club, the sleeve 48 is unlocked and pushed along the intermediate shaft portion 46 until the locking

member 56 engages the cap 52, and the pin 47 is withdrawn and the sleeve member 36 is slid upwardly within the intermediate shaft portion 46 thereby greatly reducing the shaft length so that the club may be easily packed with small hand luggage.

I claim:

1. In a universally adjustable golf club, a shaft, a head at the lower end of the shaft, an element mounted for rotatable adjustment about an axis disposed transversely of said shaft, an arcuate face on said element and curved about an axis disposed transversely of said first mentioned axis, a member secured to the head and matingly seated for arcuate slidable movement against said arcuate face, and adjustable means for securing said member and said element and said shaft in preadjusted relations to each other.

2. In a universally adjustable golf club, a shaft, an annular set of laterally projecting teeth at the lower end of the shaft, a collar mounted for axial rotation with respect to said teeth and having a similar set of teeth for selective engagement with said first mentioned teeth, a head secured to said collar for adjustment about an axis disposed transversely of the collar axis, and clamping means including a yieldable element allowing the sets of teeth to be snapped past each other to predetermined positions and for thereafter rigidly securing the head and collar in adjusted relation to each other and to said shaft.

3. In a universally adjustable golf club, a shaft, a head at the lower end of the shaft, an element mounted for rotatable adjustment about an axis intersecting the lower end of said shaft, indicating means for designating the adjusted position of said element, a partly cylindrical face on said element and curved about an axis perpendicular to said first mentioned axis, a member secured to the head, said member having a partly cylindrical wall matingly seated for slidable adjustment on said face, indicating means for showing the adjusted position of said member, and means for securing said member and said element in 45 their preadjusted positions.

4. In an adjustable golf club, a shaft, a head mounted for rotatable adjustment about an axis transversely extending through said shaft, an annular portion on said shaft, a cylindrical member rotatable with the head about said axis and having an end frictionally engageable with said annular portion, means to angularly adjust the head about another axis disposed transversely of said cylindrical member, indicating means 10 showing the angular adjustment of the head with respect to said cylindrical member, said cylindrical member and said annular portion having coextensive peripheral faces, a plurality of spaced different indicia individually marked across the 15 junction of said coextensive faces, each of said indicia having its two parts in cooperative register at a predetermined adjustment of said head, and only one of said indicia having its two parts in simultaneous register.
